UNITED STATES PATENT OFFICE.

JAMES THEODORE THOMPSON, OF SPRINGFIELD, ILLINOIS.

VALVE-GEAR FOR STEAM-ENGINES.

SPECIFICATION forming part of Letters Patent No. 721,620, dated February 24, 1903.

Application filed June 3, 1902. Serial No. 110,083. (No model.)

To all whom it may concern:

Be it known that I, JAMES THEODORE THOMPSON, a citizen of the United States, residing at Springfield, in the county of Sangamon and State of Illinois, have invented certain new and useful Improvements in Valve-Gears for Steam-Engines, of which the following is a specification.

My invention relates to valve-gears for steam-engines, and has for its object to provide a gearing for locomotive and other engines that will operate the valve directly from the cross-head of the engine without the use of the eccentrics usually employed, and thus economize in the cost of manufacture and by reducing the number of working parts save much of the friction incidental to the complicated machinery usually required to regulate the valves.

Additional advantages of my invention will appear hereinafter and by reference to the accompanying drawings, in which—

Figure 1 is a side view in elevation of my invention, showing it applied to a locomotive driving mechanism; Fig. 2, a reverse view of Fig. 1; Fig. 3, an end view; Fig. 4, a detail of the slotted link for operating the valve, and Fig. 5 a view of the pivoted arm.

Referring to the drawings, in which similar reference characters indicate corresponding parts throughout the several views, A indicates an ordinary construction of cylinder; B, a valve-chest containing the ordinary construction of slide-valve; C, the cross-head; D, the guides therefor, and E the driving-rods connecting the cross-head C with the crank-pin F on the locomotive or other driving-wheel G.

My valve-gear consists of the following structure: 1 represents a plate suspended beneath the guides D by means of rods 2, secured to said guides. 3 represents an arm pivoted to said plate 1 by means of pin 4 and having a slot 5 in its free end to receive a pin 6 on the cross-head C. It will be understood from this description of parts that the arm 3 swings with the motion of the cross-head.

7 represents a block secured to the upper side of guides D and having a pin 8 journaled thereon, one end of said pin having a link 9 keyed thereto, to the free end of which is

pivoted the valve-rod 10. On the other end of pin 8 is keyed a segmental block 11, which rides in a segmental slot 12^a in link 12, mounted thereon, said link 12 having its lower end extended and slotted, as shown at 12^b, to receive a pin 13, secured to arm 3, said arm 3 being provided with a multiplicity of holes 14 to provide for adjustment of the pin 13. 55 It will be understood from this description of the structure of link 12 and its connections that as the arm 3 swings, actuated by the cross-head C, the link 12 also swings on pin 8 as a pivot, carrying with it the segmental 65 block 11, thus oscillating the pin 8 and the link 9 and giving the valve-rod 10 a reciprocating motion, which is in turn imparted to the piston in the valve-chamber B.

In order to adjust the valve-piston in the 70 proper position to admit the steam on the side of the piston in the cylinder A desired to drive the engine in the proper direction, either forward or back, before admitting the steam, I provide a lever-arm 15, having the ordinary 75 construction of spring-catch 16, working in notches in quadrant 17.

18 represents the reach-rod, connecting the lever-arm 15 with the lever 19, keyed to the shaft 20, journaled in a boxing 21 on the 80 frame of the machine, and 22 a swinging arm keyed to shaft 20 and pivotally connected to link 22^a, which is in turn pivoted to a plate 23, secured to the slotted link 12.

24 represents a rod connecting the arm 3 85 with a suitable indicator in the locomotive-cab to enable the engineer to know the position of the arm and the consequent position of the crank-pin F and the piston in the cylinder A, so that he may know which way to 90 swing the lever should he want to reverse his engine. It will be understood from this construction that, while the engine is at rest, by the engineer swinging the lever 15 in the proper direction the link 12 may be raised or lowered 95 and shift the valve in the desired direction. The link 12 being raised or lowered in the direction of the pins 8 and 13, the segmental slot 12^a therein will twist the segmental block 11 and move the valve to the position desired. 100 After the engine is in motion the lever-arm 15 is moved back to the center of the quadrant, so that the block 11 is in the center of the segmental slot 12^a while the engine is in

motion. After the engine has stopped and it is desired to have it start again in the same direction it is only necessary to admit steam again to the cylinder, the shifting of the lever 5 15 being necessary only when it is desired to reverse the direction of the engine to move it from rest.

I have shown my invention applied to a locomotive; but it will be readily understood 10 that it is equally applicable to engines of other types, and I do not, therefore, wish to be confined to use on a locomotive-engine.

Having thus described my invention, what I claim is—

15 1. In a valve-gear, an oscillating slotted link, a pin suitably journaled, a block secured to one end of said pin to ride in said slotted link, an arm keyed to the other end of said pin and pivoted to the valve-rod, and means 20 to oscillate the link, substantially as shown and described.

2. In a valve-gear, an arm oscillated by the cross-head of an engine, a slotted link pivoted to swing with said oscillating arm, a pin suitably journaled, a block secured to one end of 25 said pin to ride in said slotted link, and an arm keyed to the other end of said pin pivoted to the valve-rod, substantially as shown and described.

30 3. In a valve-gear, a slotted link, a pin suitably journaled, a block secured to one end of said pin to ride in said slotted link, an arm keyed to the other end of said pin and pivoted to the valve-rod, means to oscillate said 35 slotted link, and means to vertically adjust said link, substantially as shown and described.

4. In a valve-gear, a slotted link directly connected with the valve-piston, connections 40 between said link and the cross-head of the engine to cause said link to oscillate, and connections between the link and reverse-lever of the engine to vertically adjust the link and actuate the valve-piston, substantially as 45 shown and described.

5. In a valve-gear, an arm pivoted to swing with the cross-head of the engine, a link having a segmental slot therein, means to cause 50 said link to swing with said arm, a pin suitably journaled, a block secured to one end of said pin to ride in said segmental slot, and an

arm keyed to the other end of said pin and pivoted to the valve-rod, substantially as shown and described.

6. In a valve-gear, a plate suspended beneath the cross-head guides, an arm pivoted to said plate and adapted to swing with the cross-head, a slotted link adapted to oscillate with said swinging arm, and connections between said slotted link and the engine valve-piston, substantially as shown and described. 60

7. In a valve-gear, a plate suspended beneath the cross-head guides, an arm pivoted on said plate and adapted to swing with the cross-head of the engine, a link having a segmental slot and a straight slot, said link connected to said arm through said straight slot, a segmental block slidably mounted in said segmental slot, and connections between said block and the valve-piston, substantially as 70 shown and described.

8. In a valve-gear, an arm pivoted to swing with the cross-head of the engine, a link connected to said arm, said link having a segmental slot therein, a pin journaled adjacent 75 to said link, a segmental block keyed to said pin slidably mounted in said slot, an arm keyed to said pin, and the valve-rod pivoted to the free end of said arm, substantially as shown and described.

9. A valve-gear comprising a plate suspended beneath the cross-head guides, an arm pivoted to said plate and having its free end slotted, a pin on the cross-head of the engine to fit into said slot, a block secured to the top of 85 said guides, a pin journaled in said block, a segmental block keyed to said pin, a link having a segmental slot to receive said segmental block and a straight slot, a pin to connect said link with said arm through said straight 90 slot, an arm keyed to said pin connected with the valve-piston, and connections between said slotted link and the reverse-lever to raise and lower said link and shift said valve-piston when the engine is at rest, substantially 95 as shown and described.

In testimony whereof I hereto affix my signature in the presence of two witnesses.

JAMES THEODORE THOMPSON.
